HINGE ADJUSTING DEVICE

Frank A. Phipps, Avondale, Mo., assignor to
Carl H. Kruse, Kansas City, Mo.

Application May 20, 1948, Serial No. 146,482

Term of patent 7 years

(Cl. D54—13)

To all whom it may concern:

Be it known that I, Frank A. Phipps, a citizen of the United States, residing at Avondale, in the county of Clay and State of Missouri, have invented a new, original, and ornamental Design for a Hinge Adjusting Device, of which the following is a specification, reference being had to the accompanying drawing, forming a part thereof, wherein:

Fig. 1 is a perspective view of the hinge adjusting device, showing my new design.

Fig. 2 is a top plan view thereof.

Fig. 3 is an end elevational view thereof.

Fig. 4 is an elevational view of the end opposite to that shown in Fig. 3.

I claim:

The ornamental design for a hinge adjusting device, as shown.

FRANK A. PHIPPS.
